Primary Examiner — Austin Murphy(74) *Attorney, Agent, or Firm* — Irina Hass(57) **CLAIM**

The ornamental design for a lint roller cover, as shown and described.

DESCRIPTION

FIG. 1 is a perspective view showing the new design for a lint roller cover;

FIG. 2 is a front view thereof;

FIG. 3 is a left side view thereof;

FIG. 4 is a rear view thereof;

FIG. 5 is a right side view thereof;

FIG. 6 is a top view thereof;

FIG. 7 is a bottom view thereof;

FIG. 8 is a perspective view thereof in an open position; and, FIG. 9 is a perspective view thereof showing the lint roller cover with a lint roller.

The portions of the lint roller cover in FIGS. 1-9 shown in broken lines are included to show features that form no part of the claimed design.
